UNITED STATES PATENT OFFICE

1,922,405

COMBUSTION BURNER

Alfred E. Stuckert, Canton, Ohio, assignor to
Wadert Co., Inc., Cleveland, Ohio, a Corpora-
tion of Ohio

Application March 7, 1930. Serial No. 433,935

19 Claims. (Cl. 110—64)

The invention relates to furnaces, and more particularly to means for burning the gases of combustion so as to eliminate smoke and produce the maximum heat from a given amount of fuel.

The objects of the improvement are to provide a burner, preferably at the rear of the fire box, through which all of the gases and smoke from the fire are passed, before entering the stack, heated air being admitted to said burner to cause complete combustion of the gases and smoke.

A further object is to locate the mouth of said burner below the level of the bed of coals in the fire box whereby all of the gases and smoke are caused to pass through the bed of live coals before entering the burner.

The above and other objects which will be apparent from the following detail description of the invention may be obtained by constructing the device in the manner illustrated in the accompanying drawings, in which

Figure 1 is a longitudinal, vertical section through a boiler furnace, showing the invention located therein;

Fig. 2, a transverse sectional view, on a larger scale, taken substantially on the line 2—2, Fig. 1; Fig. 3, an enlarged detail perspective view of one of the upper blocks of the burner;

Fig. 4, a similar view of one of the lower blocks thereof;

Fig. 5, a fragmentary sectional view through the rear portion of a so called smokeless furnace showing the invention applied thereto;

Fig. 6, a similar section taken upon a different plane;

Fig. 7, an enlarged, detail perspective view of one of the upper blocks of the form of burner illustrated in Figs. 5 and 6;

Fig. 8, a similar view of one of the lower blocks thereof;

Fig. 9, an enlarged plan sectional view of a modified form of burner, taken substantially on the line 9—9, Fig. 10; and

Fig. 10, a vertical sectional view of the same, as on the line 10—10, Fig. 9.

Similar numerals refer to similar parts throughout the drawings.

The invention is applicable to any type of furnace, and for the purpose of illustration it is shown as applied to a low pressure boiler furnace. With particular reference to the form of the invention shown in Figs. 1 to 4 inclusive, a boiler furnace is illustrated comprising the ash pit 11, grate bars 12, fire box 13 with the firing door 14 at its front end, and the stack flue 16,

all of which may be of usual and ordinary construction.

The improved smoke consuming and fuel economizing device, to which the invention pertains, may be in the form of a burner formed of a plurality of blocks, which may be made of refractory material or of metal, or of a combination of both.

Each unit or section of the burner is preferably made up of the upper and lower blocks indicated generally at 17 and 18 respectively, and these blocks may be provided at their side edges with the tongues and grooves 19 and 20 respectively, whereby the several units or sections going to make up the burner may be quickly and easily aligned and held in assembled condition.

As best shown in Figs. 1 and 2, this burner is located in the lower portion of the baffle wall 15 which forms a part of the invention, and directly adjacent to the grate bars 12, in order that all of the products of combustion must pass through said burner, and preferably first downward through the bed of live coals, before being conveyed to the stack flue 16, as will be further pointed out.

The lower block 18 preferably rests directly upon the grate bars 12, and the side portions thereof may be tapered upward as at 21, the forwardly projecting nose portion 22 being centrally located at the upper portion of the block, and the smaller projection 23 being preferably located in alignment therewith at the rear side of the block.

A central, upwardly tapered air passage 24 is provided vertically entirely through the lower block, terminating at its upper end in the narrow, elongated slot or aligned slots, as shown at 25.

Each upper block 17 is elongated and substantially T-shaped in cross section, as best shown in Fig. 2, and is provided with the forwardly and downwardly inclined hollow nose 26 adapted to register with the forward end of the nose portion 22 of the adjacent lower block.

The upright 27 of the T is formed with a narrow, centrally disposed vertical passage 29, which extends entirely through the upright 27 and communicates at its lower end with the slots 25. The sides of the upright 27 are formed with the apertures 28 communicating with the narrow vertical central passage 29.

Similar apertures 30 are formed in the lateral walls 31 of the T and in the bottom wall 32 of the hollow nose portion 26. The lower and upper blocks are assembled together as shown in Figs. 1 and 2, inverted channel blocks 33 resting upon the upwardly disposed flanges 34 at the top of the

upper blocks and upper wall of the nose 26 and closing the space between the same and the bottom of the baffle wall 15.

The end blocks 17a and 18a may be of a different structure from those above described, providing a passage 35 from the ash pit to each end portion of the inverted channel formed by the blocks 33 in order to permit heated air to enter said channel.

10 When the blocks are assembled as shown in Figs. 1 and 2, they form a series of gas passages 36 providing the only exit for gases of combustion from the fire box to the stack flue, each of these gas passages having at its inner side the 15 downwardly disposed mouth 37 located below the level of the bed of coals upon the grate bars, as indicated generally at 38.

In operating the furnace provided with this improved device, a fire is started upon the grate bars in the usual manner and after the volatiles have burned from the coal the incandescent coke remaining upon the grate bars is pushed to the rear end of the furnace covering the nose portions of the burner and causing all gases of combustion and smoke to pass downward through said incandescent coke before entering the burner.

Additional coal may then be added from time to time in the usual manner, the incandescent coke being always pushed to the rear of the furnace and maintained over the nose portions of the burner.

As the gases of combustion pass downward through the incandescent coke and into the passages 36 of the burners, they are mixed with the incoming heated air or oxygen from an outside source which passes up through the passages 24 of the lower blocks and out through the apertures 28 in the upper blocks, as well as 40 down from the channel blocks 33 and openings 30 of the upper block.

As the heated gases of combustion contact with the heated air or oxygen in the passages of the burner an intense flame is created, producing substantially complete combustion, entirely burning the gases of combustion and smoke.

Any carbon (C) gases which are formed in the fire box will be changed into CO_2 as they 50 pass through the burner; any carbon monoxide (CO) gases will be changed into carbon dioxide (CO_2); and any carbon dioxide (CO_2) gas as it passes through the incandescent bed of fuel will be changed into $2CO$ gases, and again into $2CO_2$ 55 as it passes through the burner.

Referring to Figs. 5 to 8 inclusive, a slight modification of the invention is shown to especially adapt the same to a so called smokeless boiler or furnace. In this form of the invention the 60 burner is located upon the grate bars 12a in rear of and juxtaposed to the down draft 39 and comprises the lower block 18b and upper block 17b.

The lower block preferably has the vertical 65 rear wall 40, the front wall being inclined upward toward the same as at 41 and having the central forwardly projecting nose portion 42.

A vertical passage 43 is formed through the 70 lower block terminating at its upper end in the angularly disposed slots 44 and 45 in the reduced rear portion and nose portion, respectively.

Each of the upper blocks may be of substantially H-shape having the front and rear portions 46 and 47 respectively, joined by the cen-

tral portion 48. The narrow chamber 49 in the rear portion 47 of the upper block registers with the rear slot 44 while the similar chamber 50 in the central portion of the upper block registers with the nose slot 45 of the lower block.

Apertures 51 are formed in the walls of the upper block communicating with the hollow interior thereof to discharge heated air into the gas passages 52 in order to completely burn all gases of combustion and smoke at this point.

In the modification shown in Figs. 9 and 10, all of the gas passages 54 in the head 59 lead to a single outlet 55, a square or diamond-shaped baffle 56 being preferably located at the intersection of the several gas passages, said baffle being hollow and communicating with the hollow air passage 57 in the lower portion of the head so that heated air may pass upward through the hollow baffle as well as through the apertures 58 to mix with the gases of combustion which impinge upon the baffle as they pass toward the exit 55.

I claim:

1. In an updraft furnace having a fire box, a burner block in the fire box provided with an inlet passage below the level of the fire bed in said fire box and with an outlet passage, means for causing all of the gases from the fire box to pass through said inlet passage, and the walls of said burner block being perforated for admitting additional air from outside the fire box to said outlet passage to produce complete combustion of the gases.

2. In an updraft furnace having a fire box, a burner block in the fire box provided with an inlet passage below the level of the fire bed in said fire box and with an outlet passage, means for causing all of the gases from the fire box to pass through said inlet passage, and the walls of said burner block being perforated for admitting heated air from outside the fire box to said outlet passage to produce complete combustion of the gases.

3. In an updraft furnace having a fire box, a burner block in the rear portion of the fire box provided with an inlet passage below the level of the fire bed in said fire box and with an outlet passage, means for causing all of the gases from the fire box to pass through said inlet passage, and the walls of said burner block being perforated for admitting additional air from outside the fire box to said outlet passage to produce complete combustion of the gases.

4. In an updraft furnace having a fire box, a burner block in the rear portion of the fire box provided with an inlet passage below the level of the fire bed in said fire box and with an outlet passage, means for causing all of the gases from the fire box to pass through said inlet passage, and the walls of said burner block being perforated for admitting heated air from outside the fire box to said outlet passage to produce complete combustion of the gases.

5. In an updraft furnace having a fire box, a burner block in the fire box provided with an inlet passage located below the normal level of the bed of coals in the fire box and with an outlet passage, means for causing all of the gases from the fire box to pass through said inlet passage, and the walls of said burner block being perforated for admitting additional air from outside the fire box to said outlet passage to produce complete combustion of the gases.

6. In an updraft furnace having a fire box, a burner block in the fire box provided with an

- inlet passage located below the normal level of the bed of coals in the fire box and with an outlet passage, means for causing all of the gases from the fire box to pass through said inlet passage, and the walls of said burner block being perforated for admitting heated air from outside the fire box to said outlet passage to produce complete combustion of the gases.

7. In an updraft furnace having a fire box, a burner block in the rear portion of the fire box provided with an inlet passage located below the normal level of the bed of coals in the fire box and with an outlet passage, means for causing all of the gases from the fire box to pass through said inlet passage, and the walls of said burner block being perforated for admitting additional air from outside the fire box to said outlet passage to produce complete combustion of the gases.

8. In an updraft furnace having a fire box, a burner block in the rear portion of the fire box provided with an inlet passage located below the normal level of the bed of coals in the fire box and with an outlet passage, means for causing all of the gases from the fire box to pass through said inlet passage, and the walls of said burner block being perforated for admitting heated air from outside the fire box to said outlet passage to produce complete combustion of the gases.

9. In an updraft furnace having a fire box and a grate therein, a burner block located upon the grate in the fire box and provided with an inlet passage below the level of the fire bed in said fire box and with an outlet passage, means for causing all of the gases from the fire box to pass through said inlet passage, and the walls of said burner block being perforated for admitting additional air from outside the fire box to said outlet passage to produce complete combustion of the gases.

10. In an updraft furnace having a fire box and a grate therein, a burner block located upon the grate in the fire box and provided with an inlet passage below the level of the fire bed in said fire box and with an outlet passage, means for causing all of the gases from the fire box to pass through said inlet passage, and the walls of said burner block being perforated for admitting heated air from outside the fire box to said outlet passage to produce complete combustion of the gases.

11. In an updraft furnace having a fire box and a grate therein, a burner block located upon the grate in the rear portion of the fire box and provided with an inlet passage below the level of the fire bed in said fire box and with an outlet passage, means for causing all of the gases from the fire box to pass through said inlet passage, and the walls of said burner block being perforated for admitting additional air from outside the fire box to said outlet passage to produce complete combustion of the gases.

12. In an updraft furnace having a fire box and a grate therein, a burner block located upon the grate in the rear portion of the fire box and provided with an inlet passage below the level of the fire bed in said fire box and with an outlet passage, means for causing all of the gases from the fire box to pass through said inlet passage, and the walls of said burner block being perforated for admitting heated air from outside the fire box to said outlet passage to produce complete combustion of the gases.

13. In an updraft furnace having a fire box and a grate therein, a burner block located upon the grate in the rear portion of the fire box and provided with an inlet passage below the level of the fire bed in said fire box and with an outlet passage, means for causing all of the gases from the fire box to pass through said inlet passage, and the walls of said burner block being perforated for admitting additional air from outside the fire box to said outlet passage to produce complete combustion of the gases.

14. In an updraft furnace having a fire box and a grate therein, a burner block located upon the grate in the fire box and provided with an inlet passage located below the normal level of the bed of coals in the fire box and with an outlet passage, means for causing all of the gases from the fire box to pass through said inlet passage, and the walls of said burner block being perforated for admitting heated air from outside the fire box to said outlet passage to produce complete combustion of the gases.

15. In an updraft furnace having a fire box and a grate therein, a burner block located upon the grate in the rear portion of the fire box and provided with an inlet passage located below the normal level of the bed of coals in the fire box and with an outlet passage, means for causing all of the gases from the fire box to pass through said inlet passage, and the walls of said burner block being perforated for admitting additional air from outside the fire box to said outlet passage to produce complete combustion of the gases.

16. In an updraft furnace having a fire box and a grate therein, a burner block located upon the grate in the rear portion of the fire box and provided with an inlet passage located below the normal level of the bed of coals in the fire box and with an outlet passage, means for causing all of the gases from the fire box to pass through said inlet passage, and the walls of said burner block being perforated for admitting heated air from outside the fire box to said outlet passage to produce complete combustion of the gases.

17. In an updraft furnace having a fire box and a grate therein, a burner block located above the rear portion of the grate and provided with a forwardly and downwardly disposed nose portion located below the normal level of the bed of coals in the fire box, there being an outlet passage from the fire box extending upwardly and rearwardly through said nose portion and rearward through the rear side of said burner block, there being air passages in the burner block at each side of said outlet passage, said air passages being open at their lower ends and communicating at their upper portions with said outlet passage for admitting additional air from outside of the fire box to said outlet passage to produce complete combustion.

18. In an updraft furnace having a fire box, the combination of a burner structure in the rear portion of said box, said burner structure comprising upper and lower series of blocks, each of the lower blocks being formed with vertically extending passages through it for admitting air from outside said fire box, the upper blocks being related to form gas passages having inlets and each upper block having related walls forming an air passage communicating with the air passages in the adjacent lower block, the last mentioned walls being formed with openings to supply air from said air passages into said gas passages, and means for causing all of the gases of combustion from the fire box to flow into the inlets of said gas passages.

19. In an updraft furnace having a fire box,

the combination of a burner structure in the rear portion of said box, said burner structure comprising upper and lower series of blocks, each of the lower blocks being formed with vertically extending passages through it for admitting air from outside said fire box, the upper blocks being related to form gas passages having inlets and each upper block having related walls forming an air passage communicating with the air passages in the adjacent lower block, the last men-

tioned walls being formed with openings to supply air from said air passages into said gas passages, and means for causing all of the gases of combustion from the fire box to flow into the inlets of said gas passages, said upper blocks having portions co-operating with the lower blocks to form the inlets for the gas passages below the level of the bed of coals in said fire box.
